UNITED STATES PATENT OFFICE.

SALOMON DAVIDSON, OF NEW YORK, N. Y.

ORNAMENTAL CHAIN-LINK.

SPECIFICATION forming part of Letters Patent No. 253,351, dated February 7, 1882.

Application filed December 7, 1881. (No model.)

To all whom it may concern:

Be it known that I, SALOMON DAVIDSON, a citizen of the United States, residing at New York, in the county and State of New York, have invented new and useful Improvements in Ornamental Chain-Links, of which the following is a specification:

This invention consists in a chain-link comprising a tubular body with recesses formed in said body at its ends and collars embracing the tube and fitted in said recesses; and it further consists in the tubular body recessed and provided with collars, as just specified, and having an ornamental plate fitted upon said body and engaged by said collars, as hereinafter more fully described.

This invention is illustrated in the accompanying drawings, in which Figure 1 represents a sectional side view of a chain constructed according to my invention. Fig. 2 is an end view of a chain-link. Fig. 3 is a transverse section of the same in the plane xx , Fig. 1. Fig. 4 is a transverse section in the plane yy , Fig. 1. Fig. 5 is a sectional side view of a chain-link with ornamental plate. Fig. 6 is an end view of the same. Fig. 7 is a sectional and side view of a modification of the same.

Similar letters indicate corresponding parts.

In the drawings, the letter A designates a tube, which may be square or polygonal, as shown in Figs. 2 and 3, or round, as shown in Fig. 4. This tube is cut to the required length for a chain-link, and it is provided with one or more recesses, a , which, if the tube is square or polygonal, are formed in the edges thereof; or when the tube is round the recess or recesses extend clear around, or partly around, their depth being such that they do not extend through the thickness of the metal from which the tube is formed. These recesses serve to receive the collars b , which, when compressed into the same, are firmly retained in position without solder and without swaging.

The connecting devices B , as shown in the drawings, consist of links c , which extend through the tubes A , and in the ends of which are secured rings d ; but any other suitable connecting device may be used with my chain-link.

By securing the collars b in the recesses a much time and labor are saved, since by dis-

pensing with solder not only the time for soldering is saved but the labor required for burnishing the links is materially facilitated.

In practice I use for each link two collars, 55 which are secured in recesses near the ends of the tubes used in the construction of the link.

If the tubes are square or polygonal, as shown in Figs. 5 and 6, the collars also serve to retain ornamental plates C , which are made to lay 60 flat against the sides of the tube, and the ends of which catch beneath the collars, as shown more particularly in Fig. 6. It is obvious that these plates can be ornamented in many different ways; or, if desired, my link can be used 65 without such ornamental plates; or the body of the tube may be ornamented with perforations or other devices. Furthermore, each link may be provided with one, two, or more collars, according to taste.

In order to enable me to apply the ornamental plates C to round or oval tubes, I make the same in the form of a shell, which is fitted on the tube, as shown in Fig. 7, so that the ends of the shell impinge against the collars 75 without catching beneath them.

Instead of a tube, the body of the link can be formed of a solid wire—square, polygonal, or round—and in that case the connecting devices B may consist of eyes formed in one piece 80 with the link, or attached thereto in a suitable manner, and suitable ornaments may be used, as described, with reference to the tube.

What I claim as new, and desire to secure by Letters Patent, is—

1. In a chain-link, the tube having recesses a at its ends, with one or more collars embracing the tube and fitting in said recesses, substantially as described.

2. The combination, in a chain-link, of the 90 tube A , having at its ends the collars b , fitted into recesses in the tube, and an ornamental plate arranged upon the exterior of the tube and engaging at its ends with the said collars, substantially as described.

In testimony whereof I have hereunto set my hand and seal in the presence of two subscribing witnesses.

SALOMON DAVIDSON. [L. S.]
